The ornamental design for a push/pull tow bar hitch, as shown and described.

DESCRIPTION

FIG. 1 is an environmental perspective view of a push/pull tow bar hitch showing my new design;

FIG. 2 is a front elevational view thereof;

FIG. 3 is a rear elevational view thereof;

FIG. 4 is a bottom view thereof;

FIG. 5 is a right side elevational view thereof;

FIG. 6 is a top plan view thereof; and,

FIG. 7 is a left side elevational view thereof.

The broken lines shown in all drawing views are for illustrative purposes only and form no part of the claimed design. The bar shown broken away in the middle in FIGS. 1, 4, 5, 6 and 7 is to indicate indeterminate length.
